UNITED STATES PATENT OFFICE.

EDUARD LEISSNER, OF NEW YORK, N. Y.

DESIGN FOR WALL-PAPER.

SPECIFICATION forming part of Design No. 13,151, dated August 8, 1882.

Application filed June 30, 1882. Term of patent 3½ years.

To all whom it may concern:

Be it known that I, EDUARD LEISSNER, of New York, in the county and State of New York, have invented a new and original Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

A is a band containing an ornamentation of rectangular figures resembling blocks of various shapes placed upon each other, so as to form alternately along the band figures terminating in T-shaped projections and figures terminating in H-shaped projections.

B is a band, also ornamented with a design composed of rectangular blocks. D is a band ornamented with similar rectangular blocks, set so as to form what resembles a series of steps.

E is a band with similar ornamentation, forming alternately crosses and ladder-like figures.

F is a band where the blocks form a series of figures resembling platforms approached by steps.

G is a band with an irregular ornamentation of similar blocks.

I claim—

1. The design for wall-paper, consisting of the band A, substantially as shown.

2. The design for wall-paper, consisting of the band B, substantially as shown.

3. The design for wall-paper, consisting of the band D, substantially as shown.

4. The design for wall-paper, consisting of the band F, substantially as shown.

5. The design for wall-paper, consisting of the bands A B D E F G, substantially as shown.

EDUARD LEISSNER.
